THREAD COP

Robert N. Corthell, Auburn, Maine

Application October 12, 1931. Serial No. 568,322

4 Claims. (Cl. 242—159)

This invention relates particularly to a thread cop comprising a cop tube or core on which the thread is universally or cross wound to form a thread body, which may be either conical and tapering inward from its base end to its outer end, or cylindrical and of uniform diameter from end to end.

When in use the cop is supported in a vertical position and confined against horizontal displacement. When the thread is drawn off from the body, convolutions of the thread sometimes fall to the base end of the body and are drawn thereunder and entangled so that the thread is broken by the pull exerted thereon by a sewing machine. To prevent this it is customary to confine against the base end of the thread body a cushion of yielding material which acts to support any dropped coils of thread which may collect at the base of the thread body and retain them on the outer periphery of the body so that they cannot become entangled.

The object of the invention is to provide a cop which may be either tapered or cylindrical and includes improved clamping means contracted upon, and in gripping engagement with a projecting portion of the cop, in such manner as to closely confine the cushion against the base end of the thread body.

Of the accompanying drawing forming a part 30 of this specification,—

Figure 1 is a side view partly in section of a cop having a cushion clamping member constructed in accordance with the invention.

Figure 2 is a perspective view of the clamping member shown by Figure 1.

Figure 3 is a section on line 3—3 of Figure 1.

Figure 4 shows in perspective the clamping member shown in the preceding figures and a supplemental clamping member associated therewith.

Figure 5 is a fragmentary sectional view similar to the lower portion of Figure 1, showing the two clamping members shown by Figure 4.

Figure 6 shows a clamping member slightly differing from that shown by Figures 2 and 3.

Figure 7 is a fragmentary perspective view showing a portion of a cop in an inverted position and illustrating a modification.

The same reference characters indicate the 50 same parts in all of the figures.

In the drawing, 12 designates the core, 13 the thread body wound thereon, and 14 an annular cushion of compressible material such as felt, contacting with the base end of the body 13.

55 The thread body is positioned on the core

so that a limited end portion of the core projects from the base end of the body.

The cushion 14 surrounds the projecting base end of the core and projects outward therefrom to cover the base end of the body and project 60 outward from the periphery thereof, said cushion being preferably a continuous ring of felt or thick compressible cloth.

The improved cop is characterized by the clamping means next described, quickly engageable with the projecting portion of either a tapering or a cylindrical core, and adapted to closely clamp a cushion of any desired thickness against the base end of the thread body.

I provide a clamping member of approximately 70 annular form made of resilient sheet aluminum or other material which is much harder than the material of the core, and is sufficiently thin to enable an edge portion of the member to grip the periphery of the core, the latter being made 75 of compressible material such as wood pulp.

The clamping member may be variously constructed as hereinafter described, and in any case is adapted to press a cushion 14 of any desired thickness closely against the base end of 80 the thread body, the clamping member having, in each case, a thin arcuate edge preferably a thirty-second of an inch thick, conforming to and in grasping engagement with the projecting core portion, an arcuate outer edge conforming 85 to and supporting the outer margin of the cushion, and an opening extending from the inner to the outer edge, said opening permitting a tensioning expansion of the member for a purpose hereinafter stated.

In the preferred embodiment of the invention shown by Figures 1 to 6 inclusive, 15 designates the approximately annular clamping member having relatively wide arcuate sides of sufficient width to enable the member to adequately support the cushion 14, a relatively thin arcuate inner edge 17, an arcuate outer edge substantially concentric with the inner edge, and an opening 16 extending from the inner to the outer edge. The arcuate inner edge 17 has end portions 17^a which are normally spaced apart a distance less than the diameter of the projecting core portion, and the above mentioned opening 16 is defined by extensions 19 and 20 of the inner edge 17. Said extensions are normally spaced 100 apart at their outer ends by a distance slightly greater than the diameter of the projecting core portion so that the mouth of the opening 16 is adapted to receive the projecting portion of the core when the member 15 is forced edgewise onto 105 110

said projecting portion, the arrangement being such that when the portions 17^a of the arcuate inner edge encounter the core portion, the member 15 is expanded and tensioned to permit the 5 arcuate edge 17 to embrace the core portion and automatically contract or spring inward into gripping engagement with the periphery thereof. The edge 17 may slightly indent the core as indicated at 18—18 (Fig. 3). The clamping 10 member 17 is thus firmly interengaged with the core and caused to confine the cushion against the base of the thread body, whatever the thickness of the cushion may be.

When a tapered core is employed as here 15 shown, the projecting portion is the larger end of the core, and the tapering form of the core assists the contracted inner edge 17 in confining the clamping member against downward displacement of the core.

20 One of the extensions 19 and 20 defining the opening 16 may have an outward curvature, and the other an inward curvature. This formation is intended to decrease liability of the working loose of the clamping member from the core.

25 Figures 4 and 5 show a supplemental clamping member associated with the clamping member 15 to close the gap formed by the mouth of the opening 16. The supplemental clamping member 21 may be in all respects like the member 30 15 excepting that it has a lip 22, which when the two members are assembled as shown by Figure 4, bridges the mouth of the opening 16.

The supplemental member 21 is engaged with the core by an edgewise movement opposite that 35 in which the member 15 is moved to engage it with the core. When the member 21 is not employed, the gap formed by the mouth of the opening 16 may be bridged by a ring of stiff paper placed on the member 15, a portion of 40 said ring extending across the gap.

45 One of the opening defining extensions of the inner edge 17 may have a sinuous form as indicated at 23 (Fig. 6), the other extension having an inward curvature as indicated by 24. The object of this formation is to prevent liability of the working loose of the clamping member 40 from the core.

50 In the modification shown by Figure 7 the clamping member is a normally flat-sided ring 25 having a thin core-grasping inner edge 26 and an outer edge 27 formed by the periphery of the ring, and adapted to support the margin of the cushion 14. The ring is provided with a 55 narrow opening 28, so that it has end portions in close proximity to each other, adapted to be sprung apart to tension the ring and permit its inner edge 26 to embrace the core 12, and automatically contract or spring inward thereon, to 60 permit the gripping engagement of the inner edge 26 with the periphery of the core 12, so that the member 25 may be engaged with the core with suitable firmness.

65 Although I have shown only a tapered cop, it is obvious that the core and thread body may be cylindrical instead of tapered. The tapered form is preferred.

70 The clamping means characterizing my invention may be engaged with the cop 12 at a suitable distance from the core base to permit it to clamp a cushion of greater thickness than that shown, against said base.

I claim:

75 1. A thread cop comprising a core, a thread body wound thereon, the base end of the core projecting from the base end of the body, a

compressible annular cushion covering the base end of the body and projecting from the perimeter thereof, and a clamping member of approximately annular form composed of resilient sheet material and having relatively wide arcuate sides, relatively thin inner and outer arcuate edges, and a lateral opening extending from the inner to the outer arcuate edge, said opening permitting the tensioning of the member by expansion thereof, the inner arcuate edge embracing the projecting end portion of the core, and being automatically contracted or sprung inward thereon by the tension of the member to grip the core and confine the cushion against the base end of the body.

80 2. A thread cop as specified by claim 1, the arcuate inner edge of the clamping member having ends which are normally spaced apart a distance less than the diameter of the projecting core portion, said opening being defined by extensions of said inner edge normally spaced apart at their outer ends so that the mouth of the opening is adapted to receive the projecting core portion, the arrangement being such that where the clamping member is forced edgewise onto said core portion the member is expanded and tensioned and when the inner arcuate edge embraces the core said edge is automatically contracted or sprung inward on the core by the tension of the clamping member, and grips the core and confines the cushion against the base end of the body.

85 3. A thread cop comprising a core, a thread body wound thereon, the base end of the core projecting from the base end of the body, a compressible annular cushion covering the base end of the body and projecting from the perimeter thereof, a clamping member of approximately annular form composed of resilient sheet material, and having relatively wide arcuate sides, relatively thin inner and outer arcuate edges, and a lateral opening extending from the inner to the outer arcuate edge, said inner edge having ends which are spaced apart a distance less than the diameter of the projecting core portion, said opening being defined by extensions of said inner edge normally spaced apart at their outer ends so that the mouth of the opening is adapted to receive the projecting core portion, said opening permitting the tensioning of the clamping member by expansion thereof, the inner arcuate edge embracing the projecting core portion and being automatically contracted or sprung inward thereon by the tension of the clamping member to grip the core and confine the cushion against the base end of the body, the cop comprising also a supplemental clamping member engaged, like the first mentioned member, with the projecting core portion, and provided with a clamping lip projecting into and closing the gap formed by the opening in said first mentioned member.

90 4. A thread cop comprising a tapered core, a tapered thread body wound thereon, the base end of the core projecting from the base end of the body, a compressible annular cushion covering the base end of the body and projecting from the perimeter thereof, the projecting portion of the core being the larger end thereof, and a clamping member of approximately annular form composed of resilient sheet material and having relatively wide arcuate sides, relatively thin inner and outer arcuate edges, and an opening extending from the inner to the outer arcuate edge, said opening permitting the

tensioning of the member by expansion thereof, the inner arcuate edge embracing the projecting end portion of the core and being automatically contracted or sprung inward thereon by the tension of the member to grip the periphery of the core and confine the cushion against the base end of the body, the tapered form of the core assisting the contracted inner edge in confining the clamping member against downward displacement on the core.
